UNITED STATES PATENT OFFICE.

BENJAMIN H. COZINE, OF LOUISVILLE, KENTUCKY.

AUTOMOBILE TOP.

Application filed February 1, 1919. Serial No. 274,391.

To all whom it may concern:

Be it known that I, BENJAMIN H. COZINE, a citizen of the United States, residing at Louisville, in the county of Jefferson 5 and State of Kentucky, have invented new and useful Improvements in Automobile Tops, of which the following is a specification.

This invention relates to an automobile 10 top and more particularly to means for mounting curtains under a top of usual construction, with guiding means, and means for returning the curtains to normal position beneath the top when not in use.

15 The object is to provide a structure which may be secured to the under side of a top of usual construction and which shall be inconspicuous and adapted for mounting a plurality of curtains which may be drawn 20 outwardly and then downwardly to the sides of the body, suitable guiding means being provided, said curtains being under control of elastic devices designed to return them automatically to a normal position 25 when released at their lower edges from the sides of the body.

With the foregoing and other objects in view, the invention consists in the novel construction, combination and arrangement 30 of elements hereinafter described and claimed.

In the drawings,

Figure 1 is a side view of the top, with the curtains drawn, and secured to the side 35 of the body.

Figure 2 is a section on the line 2—2 of Fig. 1.

Figure 3 is a section on line 3—3 of Fig. 1.

Figure 4 is a detail in perspective of an 40 element referred to below.

Figure 5 is a fragmentary section showing how the curtains are guided into position beneath the top, when not in use.

Figure 6 is a front view of a curtain with 45 certain elements connected therewith.

Figure 7 shows the guiding devices for the curtain connected with the surface of the body opposite to that shown in Figure 5—that is, to the outer surface.

50 Figure 8 is a sectional view in elevation of the yoke socket for supporting the guide rods.

55 In carrying out my invention I provide a central longitudinal strip designated 10 which may be secured to the under side of a top of usual construction, and on either

side of the strip 10 are other strips designated 11 and 12 and spaced from strip 10 a suitable distance.

The strips referred to may be of wood, 60 and metallic strips 13, 14, 15, and 16 are arranged beneath the outer edges of the top, and beneath the latter the curtains are guided along the line where they are deflected downwardly into position for engaging the edges of the body. 65

A plurality of transverse metallic strips are arranged at suitable intervals, a central strip being designated 17 and other strips being shown at 18, 19, 20 and 21. These 70 strips are connected at the points 25 with the central strip and arranged for slight movement with reference thereto in order that the device may be adapted to the curvature of the usual type of car top 28. These 75 members 17, 18, 19 and 20 are also connected with the other longitudinal strips. A sheet of suitable material designated 30 is mounted in the position shown and below the structure above described. 80

The curtains operate from opposite sides of strip 10 toward the outer edges of the top, two of these curtains oppositely located being designated 31 and 32, each having connection with a plurality of elastic strips 85 or bands 33 and 34 properly secured at their upper ends. The curtains themselves each

comprise an outer portion of suitable material and a main or body portion of transparent material such as is usually employed 90 for the openings in automobile curtains and the like. A rod or bar 35 extends along the lower edge of each curtain and is provided with an eye portion at each end thereof, these eyes being designated 37 and 38 95

and being guided by means of a rod extending from the edge of the body to the upper structure previously described. These rods comprise two parallel members 39 and 40 connected by a yoke portion or the like at 100 their lower ends, the two elements of the device serving to guide the eye members of two adjacent curtains. The yoke portion is received within a socket 41 on the edge of the body, a suitable engaging device such as at 42 securing the parts together. These socket members may be covered by a suitable cap or the like. If the ends of the rods are allowed to project directly into the brackets 41 (omitting the yoke), the openings in the brackets which would necessarily be provided for the ends of the rods, 105

110

may be closed by headed pins 43 when the attachment is temporarily dispensed with.

Rods covered with any suitable material 5 may be placed adjacent each pair of rods 39, 40, as shown at 45 in Figure 3, in order to secure a substantially tight joint.

In the form shown in Figure 7 the brackets 41 are attached to the opposite surface of the side of the body, in order that the 10 curtains may readily be secured by a person inside of the vehicle.

Cords may be substituted for elastic bands for raising the curtains.

What is claimed is:

- 15 1. In a device of the class described, a structure constituting an independent detachable unit and comprising a plurality of longitudinal and transverse members to be mounted beneath the top of a vehicle, curtains operating between certain of the transverse members and certain of the longitudinal members, elastic strips for mounting said curtains and permitting them to be drawn outwardly and downwardly for attachment to the sides of the vehicle body, guiding means for the curtains, means mounted on the sides of the vehicle for receiving the lower ends of the guiding means, and means for detachably securing the guiding means in the said receiving means.
- 20 2. In a device of the class described, a structure constituting an independent detachable unit and comprising a plurality of longitudinal and transverse members to be
- 25 applied to the under side of the top of a vehicle, certain of the longitudinal members near the edges of the top being spaced apart and providing guiding spaces through which the curtains may be passed, guiding devices extending from the top to the sides of the body of the vehicle, means carried by the body of the vehicle for rigidly and detachably supporting the guiding devices, curtains and guiding means carried by the lower edges thereof cooperating with the guiding devices, elastic strips connected with the side edges of the curtains and with the upper structure, said curtains being movable laterally beneath the top, then 50 downwardly into approximate contact with the sides of the body.
- 30 3. In a device of the class described, a structure proportioned to be connected with the under side of the top of a vehicle, curtains operating transversely of said structure and mounted to be drawn downwardly therefrom, guiding members carried by the lower edges of the curtains, a plurality of parallel bars between each two curtains on a given side of the vehicle, the guiding members cooperating with said bars, means 55 for connecting the bars with the sides of the body, the bars being arranged in pairs, the bars of each pair being spaced apart, and a third bar adjacent the bars of each pair, for preventing the entrance of air 60 therebetween.

In testimony whereof I affix my signature.
BENJAMIN H. COZINE.
